STOCKING

Morris Magnier, Phoenixville, Pa., assignor to Rayfel Hosiery Mills, Inc., Phoenixville, Pa., a corporation of Pennsylvania

Application August 9, 1950, Serial No. 11,687

Term of patent 14 years

(Cl. D47—7)

To all whom it may concern:

Be it known that I, Morris Magnier, a citizen of the United States, residing at Phoenixville, in the county of Chester and State of Pennsylvania, have invented a new, original, and ornamental Design for a Stocking, of which the following is a specification, reference being had to the accompanying drawing, forming part hereof.

Fig. 1 is a side view of a stocking embodying my new design; Fig. 2 is a fragmentary rear view of the stocking shown in Fig. 1; and Fig. 3 is an enlarged fragmentary view of the reinforcement portion of the design enclosed within the broken line in Fig. 2.

I claim:

The ornamental design for a stocking, as shown.
MORRIS MAGNIER.
